No. 895,000.

PATENTED AUG. 4, 1908.

J. E. BRIGHT.
PRINTER'S CHASE.
APPLICATION FILED FEB. 8, 1907.

UNITED STATES PATENT OFFICE.

JAMES E. BRIGHT, OF WASHINGTON, DISTRICT OF COLUMBIA.

PRINTER'S CHASE.

No. 895,000.

Specification of Letters Patent.

Patented Aug. 4, 1908.

Application filed February 8, 1907. Serial No. 356,338.

To all whom it may concern:

Be it known that I, JAMES E. BRIGHT, a citizen of the United States, residing at Washington, in the District of Columbia, have invented certain new and useful Improvements in Printers' Chases, of which the following is a specification.

This invention relates to printers' chases.

The object of the invention is the construction of a printer's chase in which the time required in the operation of locking is lessened and other advantages produced.

Heretofore chases used for forms in book printing have been constructed with four separate compartments, a plurality of pages being locked in each compartment, said compartments being formed by the outer rim or sides of the chase and cross-bars connecting the opposite sides and made rigid therewith.

In locking chases of the character above described it has been necessary to employ quoins and furniture adjacent the sides of each compartment formed of the outer sides of the chase thus forcing the form in each compartment against the cross-bars. In chases thus constructed it has been possible to use only one chase upon the press at a time because of the fact that were two chases placed adjacent upon the bed of the press the space occupied by the adjacent sides of the chases and the quoins and furniture abutting these sides would be so great as to render the proper folding of the pages impossible by producing varying relations between the printed matter and the edge of the page; and in case the printed sheets are cut centrally so as to fold properly an unnecessary waste of paper results. By the use of my invention this space is reduced to the desired extent whereby two chases may be used upon the press at the same time and double the work produced with each impression. To this end I dispense with the use of locking quoins and furniture on one side of the chase and provide means introduced intermediate of the form being locked; whereby the locking pressure of the side opposite the unlocked side is absorbed and uniformly transmitted to the unlocked side. By this construction two chases with their unlocked sides adjacent can be used on the bed of a press at the same time and a proper fold of the printed sheets had without cutting.

The invention here shown and described illustrates a chase comprising four compartments formed by cross-bars, but it will be

understood that the invention can be readily utilized with advantage in the construction of chases having fewer compartments.

In describing the invention in detail reference will be had to the accompanying drawing which forms part of this specification and wherein like characters of reference denote corresponding parts in the several views and in which:

Figure 1 is a top plan view of a chase embodying my invention with a form locked therein; another similar chase being shown set up adjacent thereto in dotted lines; Fig. 2 is a longitudinal section on the line *a—a* of Fig. 1. Fig. 3 is a transverse section on the line *b—b* of Fig. 1.

In these drawings the chase is constructed of the usual transverse side bars *A*, *A'* and longitudinal side bars *B*, *B'*; the words longitudinal and transverse being used with relation to the longitudinal and transverse axes of the press. The side bar *B'* is of less width than the side bar *B* as the side bars *B'* abut when a pair of chases are set upon the press for use and thereby occupy less space than if they were the same width as side bar *B*. The transverse cross-bar *C* connects the longitudinal side bars *B*, *B'* centrally and has its respective ends made rigid with the side bars *B*, *B'*. The bars *A*, *A'* have cut therein *T* shaped recesses *A²*, *A³* and a recess *C'* is cut centrally of the transverse cross-bar *C*. A longitudinal cross-bar *D* connects the transverse side bars *A*, *A'* and is capable of limited movement in the direction of the said bars *A*, *A'*. The cross-bar *D* has its ends *D¹*, *D²* formed *T* shaped adapted to rest in the recesses *A²*, *A³* respectively. The shoulders of the *T* ends of the bar *D* are shorter than the shoulders of the recesses *A²*, *A³* while the stems of the *T* recesses *A²*, *A³* are wider than the bar *D*. The said bar *D* is provided centrally with a recess *D³* corresponding to the recess *C'* in bar *C* but oppositely disposed thereto and similarly disposed to the recesses *A²*, *A³* and of a width to just easily receive the bar *C* and allow the bar *D* to move forward and backward in the recess *C'* and the recesses *A²*, *A³* in the direction of the side bars *A*, *A'*, said recesses *C'*, *A²* and *A³* being sufficiently long to permit of the desired movement of the bar *D*. The oppositely disposed recesses *C'* and *D³* cause the bars *C* and *D* to loosely inter-lock in a manner that their top and bottom surfaces register, while the bar *D* has its ends stepped at *D⁴* and *D⁵*.

whereby the top and bottom surfaces of the bar D register with the top and bottom surfaces of the bars A and A¹.

The bar D is held against displacement 5 from its seat in the recesses A², A³ by the cross-bar C which straddles the bar D centrally, the bar D being first placed in position in assembling with its stepped ends resting in the recesses A², A³. The bar C is 10 then secured in place by having its ends welded to the side bars B, B¹, said bar C overlying the bar D and preventing its displacement. In the drawing the bar C is shown integral with the bars B, B¹ as the welding of 15 the ends of the bar C to said bars B, B¹ renders the bars B, B¹ and the bar C substantially one piece.

The manner of locking the chase through the medium of the movement of the cross-bar D will be apparent. Through the utilization of the bar D constructed as shown all quoins along the side bar B¹ are dispensed with. The quoins along the side bar B when operated serving to force the cross-bar D in 25 the direction of the side bar B¹ and thus clamping the forms between the side bar B¹ and the movable cross-bar D.

Having thus described my invention what I claim as new and desire to secure by Letters Patent is:—

1. In a printer's chase an outer frame, dividing members or member forming a plurality of form compartments in said chase, and means whereby said chase is adapted to 35 be locked from three sides, the unlocked side being parallel to a dividing member.

2. In a printer's chase, an outer frame, a dividing member forming a plurality of form compartments, and means whereby the chase 40 is adapted to be locked from three sides pressure in locking being transmitted to the unlocked side through the medium of the dividing member.

3. A printer's chase having an inclosing 45 frame, a plurality of form compartments formed by cross-bars within said frame and means for locking the compartments from three sides of the inclosing frame.

4. A printer's chase having an inclosing 50 frame, a plurality of form compartments formed within said frame and means whereby said chase is adapted to be locked from three sides and the pressure transmitted to the unlocked side.

5. A printer's chase having an inclosing 55 frame adapted to be locked from three sides, a member connecting opposite sides of the frame and forming a plurality of form compartments said member being adapted to 60 transmit pressure in locking to the unlocked side.

6. A printer's chase having an inclosing frame adapted to be locked from three sides, a movable member connecting opposite sides of the frame whereby a plurality of form compartments is formed and the pressure transmitted in locking to the unlocked side. 65

7. A printer's chase having an inclosing frame adapted to be locked from three sides, a movable member connecting opposite sides 70 of the frame whereby a plurality of form compartments is formed and the pressure in locking transmitted to the unlocked side and means for securing the movable member against displacement. 75

8. A printer's chase having an inclosing frame adapted to be locked from three sides, a movable member connecting opposite sides of the frame whereby a plurality of form compartments is formed, a second member connecting and rigidly secured to the other opposite sides of the frame adapted to secure the movable member against displacement. 80

9. A printer's chase having an inclosing frame, a plurality of form compartments 85 formed within said frame and means whereby said chase is adapted to be locked from three sides and the pressure transmitted uniformly intermediate of the form being locked to the unlocked side. 90

10. A printer's chase having an inclosing frame adapted to be locked from three sides, a movable member connecting opposite sides of the frame, a second member connecting and rigidly secured to the other opposite 95 sides of the frame, whereby a plurality of form compartments are formed, a recess in the fixed member in which the movable member rests and has a limited movement.

11. A printer's chase adapted to be locked 100 from three sides and means intermediate of the form for transmitting pressure to the unlocked side from the locked side opposite thereto.

12. A printer's chase having a plurality of 105 form compartments and adapted to be locked from three sides and means intermediate of the form for transmitting pressure to the unlocked side from the locked side opposite thereto. 110

13. A printer's chase adapted to be locked from three sides and movable means independent of and co-operating with the type and furniture for transmitting pressure against the unlocked side. 115

In testimony whereof I affix my signature in the presence of two witnesses.

JAMES E. BRIGHT.
